[57] ABSTRACT

A dispenser for a gummed tape roll comprising a one-piece cardboard or equivalent blank of substantially rectangular contour, creased and bent along parallel crease lines into a substantially rectangular tube consisting of top, bottom and sidewall portions, and a closure flap adhered to one said portion, said sidewalls having oppositely disposed end closure flaps which are inwardly bent, overlapped and adhesively bonded together to form a rigid boxlike structure, said sidewalls having oppositely disposed, partially cut through roll-mounting tabs joined thereto along crease lines, said tabs being inwardly bent, overlapped and adhesively bonded together for rotatively mounting a gummed tape roll thereon, the top and contiguous sidewall portions of said structure being cut away for grasping and dispensing a tape end of a tape roll mounted on said roll mounting tabs, the top portion of said structure being provided with sharp cutting edges adjacent said cutaway portion for severing said tape; and the combination of said dispenser and a gummed tape roll rotatively mounted therein on said overlapped tabs.

GUMMED TAPE DISPENSER CARTON

This invention pertains to dispensers for gummed tape rolls, and provides a relatively cheap, throw-away type of dispenser and dispenser and gummed tape roll assembly.

Various types of relatively cheap gummed tape roll dispensers and tape roll assemblies, have appeared on the market, generally including a plastic or plastic and paper combination dispenser, intended to be thrown away when the tape is consumed, but a number of these are so fragile as to break short of complete tape consumption, and all are more expensive than that of the present invention by reason of their plastic or plastic component construction.

The dispenser of the present invention comprises in contrast, a dispenser formed from a one-piece blank of heavy cardboard or other stiff and bendable, fibrous sheet material, adapted for ready assembly into a carton within which a tape roll is rotatably mounted on overlapped and adhesively bonded tabs of the blank.

More particularly the invention comprises in a preferred embodiment, a one-piece cardboard or equivalent blank of substantially rectangular contour, transversely creased and bent along parallel lines into a substantially rectangular tube, consisting of top, bottom and sidewall portions and a closure flap adhered to one said portion, the sidewalls having oppositely disposed end closure flaps joined thereto along crease lines for overlapping and adhesive bonding, the sidewalls also having oppositely disposed, partially cut-through tabs joined thereto along crease lines, a tape roll being insertable in an end of said tube end and thence rotatably mounted on said mounting tabs by bending said tabs through the roll opening and bonding the same together, the end closure flaps being thence overlapped and bonded together to form a rigid dispensing carbon, the top and sidewalls of said tube being cut out for grasping and dispensing the tape end of said roll, and the top of said tube being also provided with a sharp cutting edges adjacent said cutout for tape dispensing in desired lengths.

The invention can best be explained as to the above and other embodiments and features of construction, by immediate reference to the accompanying drawings wherein:

FIG. 1 is a plan view of a blank in accordance with one embodiment of the invention adapted for assembling into a gummed tape roll dispenser. FIG. 2 is a perspective view of the blank of FIG. 1, partially assembled into an open ended structure and showing the manner of inserting the tape roll therein. FIG. 3 is a fragmentary sectional view of FIG. 2 as taken at 3-3 of FIG. 2. FIG. 4 is a perspective view of the completely assembled dispenser of FIG. 2 with the tape roll rotatably mounted therein. FIGS. 5 and 6 are sectional views of FIG. 4 as taken at 5-5 and 6-6 thereof.

FIG. 7 is a plan view of a dispenser blank in accordance with a further embodiment of the invention. FIG. 8 is a side elevational view of FIG. 7 as viewed from 8-8 thereof. FIG. 9 is a view similar to FIG. 8, illustrating the partial assembly of the blank of FIGS. 7 and 8 into a collapsible tube. FIG. 10 is a perspective view showing the further assembly of FIG. 9 into an open ended dispenser and the manner of inserting a tape roll therein. FIG. 11 is a perspective view showing the com-

plete assembly of the FIG. 10 showing with the tape roll rotatably mounted therein.

FIG. 12 is a plan view of a dispenser blank in accordance with a further embodiment of the invention and FIG. 13 is a perspective view thereof as partially assembled into a gummed tape dispenser carton.

FIGS. 14 and 15 are views similar to FIGS. 12 and 13 respectively of a still further embodiment of the invention.

Referring to FIGS. 1-6 inc., and more particularly for the moment to FIG. 1, the blank shown generally at 10, is made of heavy cardboard or equivalent stiff, fibrous sheet material. It is of approximately rectangular outline as shown, rectangularly notched at each of its four corners as at 11-14 inc., and also notched medially at its width on opposite sides of the blank as at 15 and 16. A pair of parallel creasing grooves extend between the medial notches 15, 16, as at 17, 18, and creasing grooves extend between each pair of adjacent corner notches, as at 19-24 inc., for zoning said blank into a top panel 25, disposed between two side wall panels 26 and 27, bottom closure flaps 28 and 29, and end closure flaps 31, 32 and 33, 34.

A double wing-like cutout portion 35 symmetrical with the top panel 25 extends into the sidewall panels 26, 27 for purposes described below. Intermediate the cutout 35 and the crease lines 19, 20, the sidewall panels are provided with oppositely disposed rectangular tabs 36, 37 which are cut through the blank on three sides of each as at 38, 39, with the tabs joined to the blank by crease lines along the fourth side of each, as at 40, 41. Secured to the top panel 25, between the cutout 35 and notch 16, is a metal strip 42, formed with serrated cutting edges as at 42a, 42b, this strip being attached to the underlying blank stock 10, in the manner best shown in FIG. 3, at 45, as by punching portions of the metal through the blank stock and flaring the same against the underside into locking engagement with the stock. It will be understood of course that the cutting element thus illustrated may be replaced by a strip of plastic or other rigid material. The flaps 32, 29, and 34 and tab 37, are coated with an adhesive, as at 50-53.

Referring now to FIG. 2 in conjunction with FIG. 1, the blank of FIG. 1, is assembled into the boxlike dispenser of FIG. 2, by bending the blank along the crease lines 17, 18, until the sidewall panels 26, 27, are normal to the top panel 25, and thence bending flaps 28, 29 into overlapping relation along crease lines 24, 21 and adhering flap 29 to flap 28. The end flaps 33, 34, are thence bent along crease lines 22, 23, into overlapping relation and bonded together by means of the adhesive 52.

At this stage of assembly, the dispenser is as illustrated in FIG. 2, namely, that of an open ended boxlike structure. With the dispenser assembled to this open ended stage as at 31, 32, an annular roll of gummed tape 56 is inserted in the open end and centered with its annular opening between the tabs 36 and 37, which are then bent inwardly into overlapping relation and adhered together by means of the adhesive 53, thereby providing an axle on which the roll 56 is rotatably mounted, in the manner illustrated in FIGS. 4-6 inc. Thereupon the end flaps 31, 32, FIG. 2, are bent inwardly along crease lines 19, 20, into overlapping relation and adhered together by means of the adhesive 50, to close said end as also illustrated in FIGS. 4 and 5.

Referring to FIGS. 4 and 5, it will now be seen that the function of the cutout 35, is to permit of grasping the end 57 of the tape roll 56, and bringing it over and adhering to the cutting element 42, for dispensing by severing the tape along a serrated cutting edge thereof.

Referring now to the embodiment of the invention shown in FIGS. 7-11 inc., and more particularly for the moment to FIG. 7, the dispenser blank therein shown generally at 60, is of substantially elongated rectangular contour, and is zoned by pairs of parallel crease lines, as at 61, 62, and 63, 64, into a bottom panel 65, interposed between sidewall panels 66, 67, and a top panel 68. A sealing flap 69, coated with an adhesive as shown, extends beyond the top panel 68. Flap 69, contains a tearout section 71, along perforated lines 72, 73, for purposes explained below. End closure flaps, as at 74, 75, and 76, 77, are integral with the sidewalls 66, 67, along crease lines, as at 78, 79 and 80, 81. A tear-off display and mounting tab 82, is integral with the sidewall 66, along perforated lines 83, 83a. The blank contains a cutout portion 84 for purposes above explained, which extends from the crease line 64 of the top panel into the contiguous sidewall panel 67. The perforation lines 83, 83a, between the opposite sidewall panel 66 and the display tab 82, contains a tear-out portion 83b, of a contour similar to the cutout portion 84 in the sidewall panel 67. The sidewalls contain partially cut-through, roll mounting tabs 85, 86, similar to those of FIGS. 1-6 inc., and also a tape cutting member 87, similar to that above described. Also flaps 69, 74, 75 and tab 85 are adhesively coated for purposes above stated.

Referring to FIGS. 7-9 inc., as the first step in assembling the blank 60 into a tape roll dispenser, the end flap 69 is looped over and adhered to the sidewall 66 over the area 87, to form an assembly, collapsible along crease lines 61-64 inc. as shown in FIG. 9. The assembly is thence converted to the open-ended boxlike configuration of FIG. 10, by overlapping and adhering the end wall flaps 75, 77, to one another. A roll of gummed tape 90, is next inserted between the open end flaps 74, 76, and rotatably mounted on tabs 85, 86, in the manner above described, and the end flaps 74, 76, bent inwardly along crease lines 78, 80 and adhered to one another to provide the final assembly shown in FIG. 11. The display and mounting tab 82, may be left attached to the wall panel 66, as shown in FIG. 10, or may be torn off along the perforation lines 83, 83a, thus tearing off with it the thereto adhered end tab portion 71, the latter along perforation lines 72, 73.

Referring now to the embodiment of FIGS. 12 and 13, the dispenser blank shown generally at 100 for FIG. 12, is zoned by crease lines 101-108 inc., into a top panel 109, sidewall panels 110, 111, a bottom panel 113, a sidewall closure flap 114, and end flaps 115-118 inc. A cutout portion 119 spans the top panel 109 and extends into the sidewall panels 111, 112, for purposes above explained. A metal or equivalent strip dispensing and cutting element 120 is secured to the top panel 109 adjacent the cutout 119. Partially cut out gummed tape roll mounting flaps 121, 122, are provided in the sidewalls 111, 112. Flaps 114, 116, 118, and tab 122 are coated with an adhesive as shown.

Referring to FIG. 13, the blank 100 of FIG. 12, is assembled into an open-ended carton as shown generally at 123 by bending the blank into rectangular tubular configuration along crease lines 101-104 inc. and ad-

hering the sidewall flap 114 to the inside of sidewall 111 in the manner shown by the cutaway portion at the lower left of FIG. 13. The end flaps 117, 118 are then folded inwardly toward one another along crease lines 107, 108, and into overlapping relation and adhered together by the adhesive on flap 118. A gummed tape roll 124 is thereupon inserted between the open end flaps 115, 116, until axially aligned with the tabs 121, 122, which are then folded inwardly along their crease lines into overlapping relation and adhered together by the adhesive on tab 122 thus rotatably to mount roll 121 thereon. The end flaps 115, 116 are then folded inwardly along crease lines 105, 106, into overlapping relation and adhered together by the adhesive on flap 116.

The embodiment of FIGS. 14 and 15 is similar to that of FIGS. 12 and 13 like elements being similarly designed and the assembly of blank 100, FIG. 14 into the carton 123 of FIG. 15 the same as that above described with reference to FIGS. 12 and 13. In the FIGS. 14 and 15 embodiment, however, the blank 100 has a tear-off, mounting and display tab 125 detachably secured to the sidewall panel 111 along a perforation line 126.

What is claimed is:

25. 1. A dispenser for a gummed tape roll comprising, a one-piece blank of stiff and bendable fibrous sheet material, of substantially rectangular contour, creased and bent along parallel crease lines into a substantially rectangular tube consisting of top, bottom and sidewall portions, and a closure flap adhered to one said portion, said sidewalls having oppositely disposed end closure flaps which are inwardly bent, overlapped and adhesively bonded together to form a rigid boxlike structure, said sidewalls having oppositely disposed, partially cut through roll-mounting tabs joined thereto along crease lines, said tabs being inwardly bent, overlapped and adhesively bonded together, the top and contiguous sidewall portions of said structure being cut away for grasping a tape end of a tape roll mountable on said roll mounting tabs, the top portion of said structure being provided with a sharp cutting edge adjacent said cutaway portion.
30. 2. A dispenser according to claim 1 wherein said cutting edge comprises a separate strip of material selected from the group consisting of metals and plastics, secured to said top portion, said strip having at least one serrated cutting edge.
35. 3. The combination of a dispenser according to claim 1 and a roll of gummed tape rotatably mounted therein on said sidewall tabs.
40. 4. A dispenser according to claim 1 wherein said closure flap is attached to a sidewall portion.
45. 5. A dispenser according to claim 1 wherein said closure flap is attached to said top portion.
50. 6. A dispenser according to claim 1 wherein said closure flap is attached to said bottom portion.
55. 7. A dispenser according to claim 1 wherein one said sidewall portion has a display card detachably secured thereto.
60. 8. A dispenser for a gummed tape roll comprising a one-piece cardboard blank of substantially rectangular contour, creased and bent along parallel crease lines into a substantially rectangular tube consisting of top, sidewalls and bottom portions, a closure flap attached to one of said portions, said sidewalls having oppositely disposed end closure flaps which are inwardly bent, overlapped and adhesively bonded together to form a

rigid boxlike structure, said sidewalls having oppositely disposed, partially cut through roll-mounting tabs joined thereto along crease lines, said tabs being inwardly bent, overlapped and adhesively bonded together, the top and contiguous sidewall portions of said structure being cut away for grasping a tape end of a tape roll mountable on said roll mounting tabs, the top portion of said structure being provided with a sharp cutting edge adjacent said cutaway portion.

9. A dispenser according to claim 8, wherein one said sidewall portion has a display card detachably secured thereto.

10. A dispenser for a gummed tape roll comprising a one-piece cardboard blank of substantially rectangular contour, creased and bent along parallel crease lines into a substantially rectangular tube consisting of top, sidewalls and bottom portions, and a closure flap attached to one of said portions, said sidewalls having oppositely disposed end closure flaps which are inwardly bent, overlapped and adhesively bonded together to form a rigid boxlike structure, said sidewalls having oppositely disposed, partially cut through roll mounting tabs joined thereto along crease lines, said tabs being inwardly bent, overlapped and adhesively bonded together, a gummed tape roll rotatably mounted on said tabs, the top and contiguous sidewalls portions of said structure being cut away for grasping and dispensing a tape end of said roll, the top portion of said structure being provided with a sharp cutting edge adjacent said

cutaway portion for severing said tape.

11. A one-piece cardboard blank adapted for ready assembly into a throw-away dispenser for a gummed tape roll, said blank being of substantially rectangular contour, transversely creased along spaced parallel lines for forming into a substantially rectangular tube consisting of top, bottom and sidewalls portions and an adhesively coated closure flap attached to one said portion, said sidewalls having oppositely disposed pairs of end closure flaps, at least one of which for each pair, is adhesively coated for overlapping and bonding to the other of said pair, said sidewalls having oppositely disposed partially cut-through tabs joined thereto along crease lines at least one of which is adhesively coated for inserting in overlapping relation through a tape roll opening and thence adhesively bonding together for rotatively mounting said roll thereon, said blank having a cutout portion in said top and sidewall portions adjacent said roll-mounting tabs for grasping a tape end of said roll in said assembled condition of said blank, and the top portion of said blank being provided with a sharp cutting edge adjacent said cutout portion for dispensing said tape.

12. A blank according to claim 11 wherein said sharp cutting edge comprises a metal strip having a serrated cutting edge, said strip being clamped to said blank.

13. A blank according to claim 11 wherein one said sidewall has a display card detachably secured thereto.
